A. E. DAVIS.
PAVEMENT AND ARMORED JOINT STRIP THEREFOR.
APPLICATION FILED NOV. 3, 1914.

1,241,826.

Patented Oct. 2, 1917.

UNITED STATES PATENT OFFICE.

ANTHONY E. DAVIS, OF PHILADELPHIA, PENNSYLVANIA, ASSIGNOR OF ONE-HALF TO
FREDERICK J. GEIGER, OF PHILADELPHIA, PENNSYLVANIA.

PAVEMENT AND ARMORED JOINT-STRIP THEREFOR.

1,241,826.

Specification of Letters Patent.

Patented Oct. 2, 1917.

Application filed November 3, 1914. Serial No. 870,017.

To all whom it may concern:

Be it known that I, ANTHONY E. DAVIS, a citizen of the United States, residing in the city and county of Philadelphia, have 5 invented a new and useful Pavement and Armored Joint-Strip Therefor, of which the following is a specification.

The object of my present invention is to devise a pavement in which an expansion 10 joint is employed, said expansion joint being formed, supported and armored in a novel manner.

With the above in view, my invention consists of a pavement, in conjunction with 15 which an armored joint strip is employed, which is supported on the earth, roadbed or foundation, so that it serves to define the contour of the finished construction.

It further consists of an expansion joint 20 in which the joint strip, which provides for expansion and contraction of the construction, is provided with an armor so that the concrete work can be finished with a rounded edge which is less likely to break 25 down under traffic conditions than if finished with a straight joint, as has heretofore been the practice.

It further consists of a novel construction and arrangement of an expansion joint 30 which serves as a joint strip and also as a templet for the workmen.

Other novel features and advantages of my invention will hereinafter more clearly appear in the detailed description.

35 For the purpose of illustrating my invention, I have shown in the accompanying drawings, forms thereof which are at present preferred by me, since the same will give in practice satisfactory and reliable 40 results, although it is to be understood that the various instrumentalities of which my invention consists can be variously arranged and organized and that my invention is not limited to the precise arrangement and organization of these instrumentalities as here- 45 in shown and described.

Figure 1 represents a perspective view of the pavement embodying my invention, certain parts thereof having been cut away to 50 more clearly show details of construction.

Fig. 2 represents a sectional view of a stake and armor plate.

Fig. 3 represents, in perspective, another 55 type of expansion joint embodying the invention.

Fig. 4 represents a sectional elevation of a portion of the construction seen in Fig. 1, but showing, in addition, a clip employed.

Fig. 5 represents, in perspective, another type of expansion joint embodying my in- 60

vention.

Similar numerals of reference indicate corresponding parts in the figures.

Referring to the drawings:—

1 designates the earth roadbed or prepared 65 foundation on which the pavement is to be placed. 2 designates a road material, such as, for example, concrete, and between adja-

cent sections, such as, for example, 3 and 4, is located an expansion joint 5, the construc- 70

tion of which will now be set forth. 6 designates a strip of expansion material which may be formed from any desired material, which I preferably form from aerated as- 75

phalt which I have described and broadly 80 claimed in my co-pending application, Serial No. 870,016, filed by me on the third day of November, 1914. The joint strip has

assembled with respect thereto the bars 7 and during the process of construction, these 80

bars and joint strip are retained in proper 85 position by means of spring clips 8 or equivalent devices, which are adapted to clamp opposite sides of the bars, and con-

sist of, in the present instance, a spring 85 which is bent upon itself to form spring arms which are maintained in closed posi-

tion by means of a ring 9. The inner face 10 of a bar 7 is preferably substantially flat 90 while the outer face thereof has near its top

an inclined wall 11 which forms a wedge- 95 shaped portion at the top of the bar, so that the concrete work is finished with a rounded edge which is less likely to break

with wear than if a straight joint was 95 formed against the bar. The outer face of a bar near its lower end is preferably tapered or inclined downwardly, as indicated at 12.

13 designates stakes, which are secured 100 to the bar 7, in the present instance, by riveting the same thereto, as indicated at

14. The stakes 13 are provided with an en- 105 larged head 15 in order that the same may be readily driven into position in the roadbed or foundation of the construction.

In the embodiment seen in Fig. 3, the construction is the same except that I employ stakes 16 which are provided with an offset or shoulder 17 so that it is only necessary 110 for the workmen to drive the stakes in as

far as the shoulder, and the top of the expansion joint will define the finished line of the road.

In the embodiment seen in Fig. 5, the joint strip 18 has on opposite sides thereof the bars 19 which have portions 20 thereof punched out in order to receive a spike or stake 21 which is provided with an enlarged head 22 so that when it is driven into position in the roadbed the expansion joint will have its upper edge at the proper height above the roadbed. If desired, portions 23 may be sheared from the bars and punched out in order to form anchoring elements to be embedded by the concrete, but such anchoring elements may be dispensed with, if desired.

In constructing the pavement, the earth, roadbed or foundation, is finished to the requisite height in any desired manner. The bars 7, which form armor plates are riveted to the stakes and two of such armors and stakes are employed on opposite sides of the joint strip, and the parts are retained in position by means of clips 8. The stakes are then driven into the earth, bed or foundation, so that they not only anchor and support the bar but support it at the proper level. Roads in which joint strips are employed are usually from fourteen to sixteen feet wide with crowns of about two inches, and in accordance with my invention, the expansion joint would be formed so as to conform to the crown of the road, and the stakes are driven in the requisite distance between the bar to the finished level. The road material is then worked to the joint and the expansion joint thus performs a double function of an expansion joint and also that of a templet. After the concrete or other material is in place, the clips which hold the two armor strips to the expansion strip are removed, and the construction is allowed to set. The expansion joint, in accordance with my present invention, is supported and carried by the earth, roadbed, or foundation, as the armor bars or plates, which protect the upper edges of the joint strip, are riveted or otherwise secured to the stakes, which latter are driven directly into the earth, roadbed, or foundation.

It will now be apparent that I have devised a novel and useful pavement and armored joint strip therefor, which embodies the features of advantage enumerated as de-

sirable in the statement of the invention and the above description, and while I have, in the present instance, shown and described preferred embodiments thereof which will give in practice satisfactory and reliable results, it is to be understood that the same are susceptible of modification in various particulars without departing from the spirit or scope of the invention or sacrificing any of its advantages.

Having thus described my invention, what I claim as new and desire to secure by Letters Patent, is:—

1. A pavement, comprising a foundation portion and a top portion, the latter consisting of a plurality of concrete sections separated from each other by expansion joints, the expansion joints having an armor extending along the upper portion of the edges of the concrete sections, and stakes secured to said armor and having shoulders intermediate their ends to limit the driving length of a stake and define the contour of the finished construction.

2. A pavement, comprising a foundation portion and a top portion, the latter consisting of a plurality of concrete sections separated from each other by expansion joints and an armor extending along the upper portions of the edges of said concrete sections at the joints which require reinforcement, and stakes rigidly secured directly to the outer side of said armor and having a head located beneath the upper face of the armor and adapted to receive an impact blow to drive said stake into said foundation portion to support the joint and define the finished contour of the pavement.

3. A pavement, comprising a foundation portion and a top portion, the latter consisting of concrete sections and expansion joints connecting said sections, said expansion joints comprising a joint strip, armor plates on opposite sides thereof each having wedge-shaped portions at their upper ends, and stakes rigidly secured directly to the sides of said armor plates beneath the wedge-shaped portions thereof and having a head located below said wedge-shaped portions and adapted to receive an impact blow to drive said stakes into said foundation portion.

ANTHONY E. DAVIS.
